BELT ATTACHABLE TAPE HOLDER

Elvin L. Boyce, Salt Lake City, Utah, assignor to Tape-
Licator, Inc., Salt Lake City, Utah

Filed June 17, 1971, Ser. No. 154,263

Term of patent 14 years

Int. Cl. D2—07

U.S. Cl. D2—400

FIG. 1

FIG. 2

FIG. 3

FIG. 4

FIG. 5

FIG. 6

FIG. 1 is a perspective view of a belt attachable tape holder showing my new design;

FIG. 2 is a side view thereof;

FIG. 3 is an opposite side view thereof;

FIG. 4 is an end view thereof, the opposite end view is substantially the same in appearance as the end view shown;

FIG. 5 is a top view thereof; and

FIG. 6 is a bottom view of the belt attachable tape holder.

I claim:

The design for a belt attachable tape holder, as shown.
